TELEVISION FORUM TABLE

Dan Golenpaul, New York, N. Y.

Application March 3, 1949, Serial No. 79,330

2 Claims. (Cl. 311—1)

1

This invention relates to a combination article of furniture and relates more particularly to a novel table designed primarily, although not exclusively, for use in television broadcasts of programs of the "quiz" variety and others wherein there are a limited number of participants who are called upon from time to time to speak.

An important object of the invention is to provide a novel table of this character which will allow the participants to be grouped in a relatively small area, substantially equally spaced from the television camera, without, however, appearing to be crowded.

Yet another object of the invention is to provide a table having a table top with an apron-like supporting means therefor, the table top having a curved rear edge and a front opening provided with display means for exhibiting charts or the like.

In the drawing:

Fig. 1 is a plan view of a combination table embodying the present invention.

Fig. 2 is a front elevation thereof.

Fig. 3 is a central vertical section taken on line 3—3 of Fig. 2.

Fig. 4 is a perspective view of one of the component parts of the table.

Fig. 5 is a perspective view of another of the component parts thereof.

Fig. 6 is a broken section taken on line 6—6 of Fig. 2.

The table of the present invention may be constructed in the two sections 8 and 9 illustrated in Figs. 4 and 5, respectively, the latter section forming a table supporting member replacing the usual legs and comprising a front vertical wall 10 and terminal or wing portions 11 and 12 which extend rearwardly of the front wall at less than a right angle thereto. In the center of the front wall there is formed a generally rectangular opening 13 extending downwardly from the upper edge thereof.

The other section illustrated in Fig. 4 comprises a table top 14 whose rear edge 15 is convexly curved and constitutes an arc of a relative large circle. The front is composed of two spaced, straight edge sections 16 and 17 and the side edges 18 and 19 are disposed at less than a right angle to the front edge sections and preferably bear the same angular relationship to such front edges as wing sections 11 and 12 bear to front wall 10. Between front edge sections 16 and 17 there is a generally rectangular opening extending rearwardly substantially one-half the width of the table top.

2

A display rack comprises a downwardly and forwardly inclined wall 22 whose upper edge 23 is joined to the rear edge of the opening in the table top. The opposed ends of the wall 22 are joined to the table top by generally triangular wall 24 and at its lower end, wall 22 is connected with a bottom wall or shelf 25 which is disposed generally at right angles to inclined wall 22. For the purpose of imparting rigidity to the structure 5 as well as giving it a more finished appearance, the front edge and the end edges of the table top are constructed in the manner illustrated in Fig. 6 and include a rail 26 underlying such edges and a relatively thin facing strip 27.

15 This facing strip preferably extends downwardly along the forward edges of end walls 24, as shown at 30 and 31 and also along the forward edge of base wall 25 as indicated at 32. The lower edge 33 of the opening 13 in front wall 10 10 is inclined at the same angle as rear wall 22 of the display rack, said edge 33 supporting the display rack as shown in Fig. 3.

It will be noted from Fig. 1 that front wall 10 is spaced inwardly of the forward edge of the 25 table top and that the wing portions 11 and 12 terminate at the rear curved edge 15 of such table top. If the parts are separately formed as shown in Figs. 4 and 5 it is only necessary to suitably secure the table top to the upper edges of members 10, 11 and 12 and the table is ready for use.

The performers sit to the rear of curved edge 15 and there is ample leg room between this edge and members 10, 11 and 12. A stack of the charts (not shown) suitably arranged in proper order 30 is placed on the display rack and the performance may proceed.

The charts on the display rack are for the convenience of the studio audience whereas a duplicate of each chart is successively displayed to the 40 participants of the round table discussion by an attendant standing forwardly of the table and to one side thereof, out of the range of the camera. In most instances the master of ceremonies will not be one of the parties sitting around the rear 45 curved edge of the table.

By confining the performers within this relatively small area and at a substantially equal distance from the camera, there is obtained a high degree of definition and visibility with no unnecessary detail.

While one form or embodiment of the invention has been shown and described herein for illustrative purposes, and the construction and arrangement incidental to a specific application 55 thereof have been disclosed and discussed in detail, it is to be understood that the invention is

limited neither to the mere details or relative arrangement of parts, not to its specific embodiment shown herein, but that extensive deviations from the illustrated form or embodiment of the invention may be made without departing from the principles thereof.

What I claim is:

1. A combined table of the character described comprising a table top and a continuous supporting means therefor, such table top being formed with a convexly curved rear edge, a substantially straight front edge and straight side edges disposed at obtuse angles relative thereto, and having a generally rectangular opening extending rearwardly from the forward edge midway between the ends of the table, a display rack disposed within such opening and comprising a chart-supporting wall extending from the rear edge of such opening downwardly and forwardly, the upper portions of said wall terminating on the plane of said table top, end walls connecting such wall with the table top, and a rearwardly inclined wall at the lower end of the chart supporting wall, the supporting means comprising a vertical wall disposed to the rear of and substantially parallel with the front edge of the table top and extending a major portion of the length thereof, and rearwardly inclined wing portions at opposite ends of said vertical wall disposed parallel relative to said table top side edges.
2. A combined table of the character described comprising a table top and an apron-like supporting means therefor, such table top being formed with a convexly curved rear edge, a substantially straight front edge and a generally

rectangular opening extending rearwardly from the forward edge substantially midway between the ends of the table, a display rack disposed within such opening and comprising a chart-supporting wall extending from the rear edge of such opening downwardly and forwardly, end walls connecting such wall with the table top, and a rearwardly inclined wall at the lower end of the chart supporting wall, the supporting means comprising a vertical wall disposed to the rear of the front edge of the table top and extending a major portion of the length thereof, and rearwardly inclined wing portions at opposite ends of said vertical wall which terminate at the rear curved edge of the table top, said vertical wall having a central, rectangular opening extending downwardly from its upper edge, the lower edge of the opening forming a support for the chart-supporting wall.

DAN GOLENPAUL.
